UNITED STATES PATENT OFFICE.

HUBERT A. MYERS, OF TOLEDO, OHIO.

REPEATING ATTACHMENT FOR PHONOGRAHS.

1,330,603.

Specification of Letters Patent. Patented Feb. 10, 1920.

Application filed May 23, 1918. Serial No. 236,209.

To all whom it may concern:

Be it known that I, HUBERT A. MYERS, a citizen of the United States, and resident of Toledo, in the county of Lucas and State of Ohio, have invented a certain new and useful Repeating Attachment for Phonographs; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an attachment for phonographs, and particularly to means automatically operable at a predetermined point in an inward movement of the tone-arm to return it to initial playing position.

The object of my invention is the provision of a simple and efficient mechanism of the class described, which is automatically operable, at a predetermined point in an inward movement of the associated tone-arm, to raise the stylus from engagement with the record, quickly return the arm and attached mechanism to initial playing position, and then lower the stylus to engage the record to repeat the playing of the piece, such repeating action being successively continued until the machine runs down or is stopped.

A further object of the invention is the provision of simple and efficient means for retarding the downward swinging or record engaging movement of the customary stylus of machines of the class described when adjacent to the record, whereby the stylus is caused to lightly engage the record even though the sound-box or part by which it is carried may be dropped, thus preventing injury to the record which so frequently occurs by reason of the accidental or careless dropping of the sound-box and stylus thereon.

The invention is fully described in the following specification, and while, in its broader aspect, it is capable of embodiment in numerous forms, a preferred embodiment thereof is illustrated in the accompanying drawings, in which—

Figure 1 is a plan view of a portion of a phonograph embodying my invention and in playing position. Fig. 2 is an enlarged sectional detail taken on the line 2—2 in Fig. 1

of a portion of the means employed to check the downward or record engaging movement of the stylus-arm. Fig. 3 is an enlarged side elevation of the rotary escapement controlled member of the attachment, with such member in stylus raising engagement with a record. Fig. 4 is a similar view, with the member out of engagement with the record, or in playing position. Fig. 5 is a perspective view of the mechanism embodying my invention, with the tone-arm to which it is secured partially broken away and with the rotary member in record engaging or stylus lifting position. Figs. 6 and 7 are enlarged fragmentary top plan views of the attachment, with parts broken away and with the rotary member in record engaging position in one and released position in the other, and Fig. 8 is a side elevation of the outer escapement-operating trip means in operative relation to the rotary record carrying table of the machine.

Referring to the drawings, 1 designates the case of a phonograph on the top of which is mounted the customary rotary table 2, on which a record 3 is centered by a pivot-stud 4 rising from the center of the table through and above a center opening in the record, as well understood in the art. The customary tone-arm 5 is adapted to extend over the table 2 from one side thereof for horizontal swinging movements relative thereto, and attached to the free end of this arm, in the case of a vietrola, is a vertically swinging goose-neck 6, which carries a sound-box 7 at its free end. The record engaging stylus projects from this sound-box, as is well understood in the art.

The mechanism embodying the invention comprises a frame-arm 8, which is rigidly clamped to the goose-neck 6 adjacent to its inner end by a clamping means 9, and has its rearwardly projecting arm provided with a cross-head 10 at the rear of the goose-neck and, in the present instance, substantially at right angles to the axis of the tone-arm 5. Bearing-ears 11 project upward from the inner end of the cross-arm and a check-lever 12 is pivoted to such ears for vertical rocking movements. The short arm of this lever projects under the tone-arm and carries an adjusting screw 13 for upward contact against the under side of the tone-arm, and the other or long arm of the lever pivotally

carries a dash-pot 14, which works down over a plunger 15, the stem 16 of which is pivotally anchored at its lower end to the adjacent end portion of the cross-arm 10, as 5 best shown in Fig. 2.

It will be understood that the frame 8, 10 is fixedly carried by the goose-neck 6 for vertical rocking movements therewith and that the screw 13 in the check-lever 12 is so 10 adjusted that it will normally have contact with the underside of the tone-arm slightly before the stylus carried by the sound-box 7 has been lowered sufficiently to engage the record, thus retarding the further downward 15 movement of the sound-box and stylus, due to the retarding action of the dash-pot 14 and plunger 15 on the lever 12. In other words, if the sound-box and goose-neck are 20 suddenly dropped from raised position the sudden downward movement of the same will be stopped slightly before the stylus has 25 engaged the record and the parts will then be permitted to slowly lower so that the stylus will gradually move into engagement 30 with the record by reason of the checking action of the check mechanism on the goose-neck. This is an important feature of my invention, aside from its use in connection with the repeater mechanism, as injury to the record is prevented should the sound-box and goose-neck be accidentally or carelessly dropped from raised position.

A post 17 projects downward from the forward end of the frame-arm 8, being preferably attached thereto for rotary horizontal adjustment, and carries a forwardly projecting fork 18 at its lower end. A shaft 19 connects the free end portions of the arms of this fork, being journaled therein for free 40 rotary movement, and an escapement-wheel 20 is fixed to the shaft for rotary movements between the fork-arms. This wheel carries a roller 21 at one side of its axis, with the periphery of said roller at the outer side of 45 the roller axis, substantially tangential to the circle of the wheel periphery to serve as a rolling support for said wheel when in engagement with the record, as hereinafter more fully described. The periphery of the 50 wheel 20, at a different side of its axis from the position of the roller 21 relative to the wheel axis, is flattened, as at 22, or such flattened portion is so positioned with respect to the axis of the wheel that when such portion 55 is disposed immediately over a subjacent record the wheel will be free from peripheral or supporting contact therewith, as illustrated in Fig. 4. The portions of the wheel periphery which connect the portion thereof 60 carrying the roller 21 and the portion 22 are preferably connected by arcuate portions 23 and 24. The roller 21 and surface 22 are preferably disposed at an angle to each other which is greater than a right angle so that 65 when the surface 22 is adjacent to a record

the roller 21 will be disposed at the rear side, in the present instance, of a vertical line intersecting the axis of the wheel.

An escapement-lever 25 is fulcrumed for horizontal rocking movements to the lower end portion of the post 17 and is disposed, in the present instance, in a slot 26, which is provided longitudinally in the fork 18. This lever is provided with a pair of escapement-fingers 27 and 28, which project transversely 75 from the lever, one at each side of its fulcrum and in straddling relation to the inner or adjacent edge portion of the escapement-wheel 20. When the lever is rocked in one direction the finger 27 engages under a stop-pin 29 projecting from the side of the wheel 20 in advance of the axis of the roller 21, relative to the direction of turning of said wheel, and when the lever is rocked in the opposite direction the finger 28 engages 85 under a stop-pin 30 projecting from the opposite side of the wheel adjacent to the arcuate surface 24 thereof and intermediate its ends. The stop-pin 29 is so positioned with respect to the roller 21 and portion 22 90 of the escapement-wheel that when in stop contact with the escapement-finger 27, as shown in Figs. 4 and 7, the surface 22 is adjacent to and substantially parallel to the surface of a subjacent record and the roller 95 21 is disposed at the rear side of the wheel axis in such position that when the pin 29 is released from engagement with the escapement-finger the additional weight of the side of the wheel which carries the roller 21, 100 which weight may be in said roller, causes an automatic turning of the wheel in counterclockwise direction to place the roller into wheel supporting engagement with the subjacent record. The movement of the roller 105 21 to this position is augmented by the arcuate surface 23 thereof being engaged by the top rotating surface of the record, which rotation is in a direction to impart counterclockwise rotation to the wheel 24 when in 110 engagement therewith. When the wheel has turned to place the roller 21 thereof in supporting engagement with the record, as shown in Fig. 3, the stop-pin 30 will have moved into stop contact with the escapement-finger 28, which now stands in movement obstructing relation thereto, as shown in Fig. 6.

When the roller 21 is in wheel supporting engagement with a rotating record and the lever 25 is rocked to disengage the escapement finger 28 from the pin 30 and to place the finger 27 in the path of movement of the pin 29, the movement of the record will impart a forward or counterclockwise rotation to the wheel 20 and return the wheel 120 to the inoperative position shown in Fig. 4 from the operative position shown in Fig. 3, the rotation of the wheel being stopped by the engagement of the pin 29 with the escapement finger 27 when the reduced sur- 125 130

face 22 of the wheel is in register with the record.

The escapement lever 28 is provided at its inner end with a pivotally adjustable finger 31, which is clamped at its inner end for frictional turning movements relative to the lever by a bolt 32, or in any other suitable manner, and is positioned to have contact with the upper projecting end of the record centering post 4 of the table when the tone-arm 5 and attached parts have swung inward a predetermined extent. The engagement of the finger 31 with the center post during an inward swinging movement of the tone-arm imparts a rocking movement to the escapement lever 25 in a direction to release the escapement finger 27 from the stop-pin 29 and the escapement wheel, thereby permitting an automatic or gravity turning of said wheel to place the roller 21 thereof in wheel elevating engagement with the record and effecting a raising of the stylus a sufficient extent to free the record. The tone-arm 5 is now free to swing outward and such outward movement is occasioned by the rotating of the record in contact with the roller 21 due to the relative positions of the axes of the record and tone-arm and to centrifugal action, as is apparent. This outward swinging movement of the arm is quickly effected and when the arm has reached a predetermined point in such movement the outer end of the escapement lever 25, which is angled for such purpose, engages a trip member 33, and this effects a rocking of the escapement lever to release the stop engagement of the finger 28 with the pin 30 and to move the finger 27 into the path of movement of the pin 29 on the escapement wheel, thus permitting a return of the wheel to its inoperative position and effecting a lowering of the stylus into playing engagement with the record. The trip member 33 may be carried at one side of the table 2 by a plate or supporting standard 34, which may have a part thereof projected under the table and be adjusted radially thereof to permit a varying of the point of engagement of the lever with the stop member to meet the requirements or size of the record being played. In the present instance, the trip member 33 is shown as being pivoted to the standard 34 and in the form of a lever with one arm shorter than the other, the long arm being positioned to have stop contact with the escapement lever when a 10" record is being played and a short arm being positioned to have contact with the escapement lever when a 12" record is being played and the member is turned into position therefor.

The operation of my attachment is as follows: The finger 31 and trip member 33 are first adjusted to suit the record being played so that the finger 31 will coöperate

with the center stud 4 to trip the escapement lever in one direction immediately upon the completion of the playing of the recorded matter on the record, or substantially so, and the outer end of the escapement lever will engage the trip member 33 when the tone-arm and parts carried thereby have been returned to initial playing position. After such adjustment has been effected, the operator lowers the sound-box 70 to place the stylus in engagement with the record and when the stylus is adjacent to the record, its lowering movement is checked or retarded by the upward engagement of the short arm of the check lever 12 with 75 the under side of the tone-arm, so that the further downward movement of the stylus will only be permitted as the dash pot 14 and plunger 15 relatively move for such purpose. In this connection it may be stated 80 that the weight of the check mechanism or the portion of the attachment which is disposed in the rear of the goose-neck 6 is so regulated with respect to the weight of the portion of the attachment which is disposed 85 in advance of its point of connection with the tone-arm 6 that each of said portions of the attachment preferably counterbalances the other. In this manner, the weight or pressure of the stylus on a record is the 90 same as if the attachment were not connected to the goose-neck. When the stylus has lowered into engagement with the record, the escapement wheel 20 is in inoperative position, or with its reduced surface 95 100 adjacent to the record. When the playing of the record is completed, the tripping of the escapement lever 25, to release the finger 27 from stop engagement with the pin 29, will be effected by engagement of 105 the lever finger 31 with the record centering stud 4, thus permitting an automatic or gravity turning of the escapement wheel from the position shown in Fig. 4, to that shown in Figs. 3 and 5 to place the roller 21 110 in engagement with the record to effect a raising of the stylus from record engaging position. The raising of the stylus, however, is effected as soon as the peripheral surface 23 of the wheel turns into contact 115 with the record, and, instantly upon the raising of the stylus, the tone-arm and attached parts begin their outward swinging movements by reason of the driving action of the rotating record on the escapement 120 wheel. When the tone-arm has swung outward a sufficient extent for the outer end of the escapement lever 25 to engage the trip member 33, such lever is rocked to release the engagement of its finger 28 with 125 the stop-pin 30, thereby permitting a return of the escapement wheel to its inoperative position (shown in Figs. 4 and 7) by reason of the rotating of the record in contact first with the roller 21 and then with 130

the peripheral surface 24 of the wheel, as is apparent. The turning of the escapement wheel to its inoperative position lowers the stylus into engagement with the record to repeat the playing of the piece. It is thus evident that in this manner the playing of a record may be automatically repeated as many times as desired, or until the phonograph runs down or is stopped.

10 While I have particularly illustrated and described my attachment for use in connection with phonographs of the Victor type, it is apparent that it may be attached to the sound-box carrying members of practically 15 all phonographs on the market with only slight changes in its construction, which changes fall within the scope of the invention and claims.

I wish it understood that my invention 20 is not limited to any specific construction, arrangement or form of the parts or to the manner of attaching thereof to phonographs of different makes and styles, as it is capable of numerous modifications and changes 25 without departing from the spirit of the claims.

Having thus described my invention, what I claim as new, and desire to secure by Letters Patent, is:—

30 1. In a phonograph, a tone-arm mounted for horizontal swinging movements, a sound box carrying member pivoted to said tone-arm for vertical swinging movements relative thereto, a bracket fixed to said member, 35 a lever fulcrumed to said bracket transversely of and extending at one end under said tone-arm, an adjustable contact carried by said lever for engagement with said tone-arm at a predetermined point in a lowering movement of the member whereby a 40 rocking movement is imparted to the lever during a continuation of such movement, and dash pot and plunger means yieldingly connecting the opposite end of said lever 45 and bracket and operating to resist a tone-arm actuated movement of said lever.

2. In a phonograph, a tone-arm mounted for horizontal swinging movements, a sound box carrying member pivoted to said tone-arm for vertical swinging movements relative thereto, a lever carried by said member and extending at one end under said tone-arm to engage and be rocked thereby at a predetermined point in a lowering movement of the member, and means 55 yieldingly connecting the opposite end of said lever and member and operating to resist a tone-arm actuated movement of said lever.

60 3. In a phonograph, a tone-arm, a sound box carrying goose-neck pivoted to said arm for vertical swinging movements, and means carried by said goose-neck adjacent to its pivot for vertical swinging movements 65 therewith and operable to coact with said

tone-arm to yieldingly retard said goose-neck at a predetermined point in its lowering movement and means comprising a part of a repeating attachment carried by the goose-neck to counterbalance the weight of 70 said first means thereof.

4. In a phonograph, the combination with a vertically and horizontally movable stylus carrying member, and a record being played, of means carried by said member 75 and rotatably movable in one direction into and out of record engaging position and adapted, when in record engaging position, to elevate said member relative to the record to free the stylus therefrom, trip means 80 for successively stopping said rotatable means in record released and engaged positions and automatically operable at predetermined points in the inward and outward movements of said member to release said 85 rotatable means to have rotary movements to respectively engage and release said record, said rotatable means being automatically movable from record releasing to engaged position, and the rotation of said 90 record actuating a return of the member to initial playing position when the rotatable means is in engagement with the record, and actuating a return of said means to record released position when released for such 95 purpose by the trip means.

5. In a phonograph, the combination with a vertically and horizontally movable stylus carrying member and a subjacent rotatable element, of means carried by said 100 member and operable, when in one position, to rest on said element and coöperate therewith to impart predetermined vertical and horizontal movements to said member and to move said means to disengage the element, and means operable at predetermined 105 points in a horizontal movement of said member to permit predetermined movements of said first means relative to said member to engage and release said element, said 110 first means being normally movable from element released to element engaging position.

6. In a phonograph, the combination with a vertically and horizontally movable stylus carrying member and a subjacent horizontally rotatable element, of an escapement mechanism carried by said member and automatically operable at a predetermined 115 point in one horizontal movement of said member to engage said element and elevate the member with respect thereto and at a predetermined point in the opposite horizontal movement of the member to release the element and lower said member, the 120 movement of said element in engagement with said mechanism effecting a horizontal movement in one direction of said member and a portion of the operating movements 125 of said mechanism.

7. In a phonograph, the combination with a vertically and horizontally movable member and a subjacent rotatable element, of an escapement wheel rotatably carried by said member and automatically operable to move from inoperative to operative position when released for such purpose and, when in operative position, to coact with said element to elevate the member with respect thereto.
- 10 the rotation of said element, when the wheel is in engagement therewith, effecting an outward movement of the member relative to the element axis and urging a rotation of the wheel in one direction, and escapement means operable at predetermined points in a horizontal movement of said member to permit predetermined step-by-step rotary movements of said wheel.
8. In a phonograph, a rotating member, a horizontally swinging tone arm overhanging said member, a second arm carried by said tone arm for vertical swinging movements relative thereto and having a stylus for engagement with the member, an element 25 movably carried by said second arm and movable into and out of stylus elevating engagement with said member, means operable at predetermined points in inward and outward swinging movements of said arm to release said element to permit it to move, respectively, to operative and inoperative positions, said members coacting with said element, when in operative position, to impart an outward swinging movement to said tone 30 arm and to move the element to inoperative position when released for such purpose.
9. In a phonograph, a horizontally swinging arm, a stylus carrying member carried by said arm for vertical movements relative thereto, a rotating record, a member elevating element movably connected to said member and operable, when in one position, to coact with the record to elevate the member relative thereto, swing said arm outward and then move the element to lower the member into playing position, and means automatically operable to periodically engage and release said element to permit intermittent movements thereof.
10. In a phonograph, a horizontally movable arm, a stylus carrying member carried by said arm for vertical movements relative thereto, a rotating record, a rotatable member elevating element movably connected to said member and operable, when in inoperative position of its movement, to stand free from said record, and when in operative position of its movement, to coact with the record to elevate the member relative thereto, move said arm outward a predetermined extent and then move the element to inoperative position to lower the member to place its stylus into engagement with the record, and means automatically operable,

at predetermined points in a movement of said arm, to release and engage said element to permit partial rotary movements thereof.

11. In a phonograph, a horizontally movable arm, a stylus carrying member carried by said arm for vertical movements relative thereto, a rotating record subjacent to the stylus of said member, a rotatable member elevating element connected to said member and having a peripheral portion which, when adjacent to the record, stands spaced therefrom when the member is resting thereon, and a portion which, when adjacent to the record, has member elevating contact therewith and is actuated by the rotation of the record to move the member and arm outward a predetermined extent and then to turn the element to lower the member, and escapement mechanism coacting with said element to control its rotation and automatically operable at predetermined points in the inward and outward movements of said arm to permit predetermined rotary movements of said element.

12. In a phonograph, a horizontally movable tone-arm, a stylus carrying member carried by said arm for vertical movements relative thereto, a rotating record subjacent to said member, a rotatable member elevating element connected to the member and having a portion at one side of its axis which normally moves into record engaging position to coact therewith to elevate the member free from the record and which is provided with an anti-friction record engaging surface, move the member and arm outward a predetermined extent and then turn the element to disengage the record and lower the member, and escapement mechanism coacting with said element to control its rotation and automatically operable, at predetermined points in the inward and outward movements of the arm, to permit said element to move, respectively, to member elevating and lowering positions.

13. In a phonograph, a horizontally movable tone-arm, a stylus carrying member carried by said arm for vertical movements relative thereto, a rotating record subjacent to said member, a rotatable member elevating element connected to the member and having a portion at one side of its axis which normally moves into record engaging position to coact therewith to elevate the member relative to the record and which is provided with an anti-friction record engaging surface, move the member and arm outward a predetermined extent and then turn the element to disengage the record and lower the member, said element having circumferentially spaced side stops, and an escapement lever fulcrumed adjacent to said element and having fingers which alternately engage first one and then another of said stops when the lever is rocked, said

- lever being automatically rocked in one direction when the tone-arm is at a predetermined point in an inward movement thereof, and vice versa when the tone-arm 5 is at a predetermined point in an outward movement thereof.
14. In a phonograph, a horizontally movable tone-arm, a stylus carrying member pivoted to said arm for vertical movements, 10 a subjacent rotating record, a frame fixed to said member, a rotatable member elevating means carried by said frame and having a portion at one side of its axis which normally moves into record engaging position 15 to coact therewith to elevate said member to free its stylus from the record, move the tone-arm outward a predetermined extent, and then turn the means to disengage the record and lower the member, and mechanism normally holding said means against 20 rotation and automatically operable, at a predetermined point in each stroke of the tone-arm, to release the element.
15. In a phonograph, a horizontally movable tone-arm, a stylus carrying member pivoted to said arm for vertical movements, 25 a subjacent rotating record, a frame fixed to said member, a rotatable member elevating means carried by said frame and having a portion at one side of its axis which normally moves into record engaging position 30 to coact therewith to elevate said member to free its stylus from the record, move the tone-arm outward a predetermined extent, and then turn the means to disengage the record and lower the member, an escape- 35 ment lever carried by said frame and co-acting with said means to permit predetermined step-by-step rotary movements there- 40 of when the lever is rocked, and means positioned to engage and rock said lever in different directions at a predetermined point in each stroke of said arm.
16. In a phonograph, a horizontally swing- 45 ing tone-arm, stylus carrying means carried by said arm for vertical movements, a subjacent rotating record, mechanism connected to said means and automatically operable, at a predetermined point in one stroke of the 50 tone-arm, to engage and coöperate with the record to raise the means to release its stylus from the record, swing the tone-arm outward a predetermined extent and then lower the means to engage its stylus with the record, and means carried by said stylus carrying means for counterbalancing the weight 55 of the mechanism on the stylus carrying means and adapted to coact with the tone-arm to retard a lowering of said last means.
17. In a phonograph, a horizontally swing- 60 ing tone-arm, a stylus carrying member carried by said arm for vertical movements, a subjacent rotating record, mechanism connected to said member and automatically 65 operable, at a predetermined point in one stroke of the tone-arm, to engage and co- 70 operate with the record to raise the member to release its stylus from the record, swing the tone-arm outward a predetermined extent, and then lower the member to engage its stylus with the record, and means counterbalancing the weight of said mechanism on the member and operable to yieldingly retard the record engaging movements of the member stylus. 75
18. In a phonograph, a horizontally and vertically movable stylus carrying member, a rotating record subjacent to said member, a member elevating element movably connected to said member and operable, when 80 in one position, to coact with the record to elevate said member relative thereto, move it outward and then lower the member into playing position, and means automatically operable to periodically engage and release 85 said element to permit intermittent movements thereof.
19. In a phonograph, a stylus carrying member mounted for vertical and horizontal movements, a rotating record subjacent to 90 said member, elevating means movably connected to said member and operable, when in one position relative to the member, to coact with the record to elevate the member to free its stylus from the record, swing the member 95 outward a predetermined extent and then move said means to lower the member to place its stylus in engagement with the record, and means automatically operable at a predetermined point in the inward and outward swinging movements of said member 100 to permit said first means to move respectively to member elevating and lowering positions.
20. In a phonograph, a stylus carrying member mounted for vertical and horizontal movements, a rotating record subjacent thereto, an elevating means movably connected to said member and operable, when 105 in one position of its movement relative to the member, to coact with the record to elevate the member to free its stylus from the record, swing the member outward a predetermined extent and then move said means to lower the member to place its stylus in 110 engagement with the record, said means having spaced stops thereon, and an escape- 115 ment lever fulcrumed adjacent to said means and having fingers which alternately engage first one and then another of said stops 120 when the lever is rocked, said lever being automatically rocked in one direction when the tone-arm is at a predetermined point in an inward movement thereof, and vice versa, when the tone-arm is at a predetermined 125 point in an outward movement thereof.
21. In a phonograph, a stylus carrying member mounted for vertical and horizontal movements, a rotating record subjacent to the stylus of said member, a rotatable mem- 130

ber elevating element connected to said member and having a peripheral portion, which, when adjacent to the record, stands spaced therefrom when the stylus carried

and escapement means automatically operable to periodically engage and release said element to permit intermittent rotary movements thereto. 45

- 5 by the member is resting on the record, and having a portion, which, when adjacent to the record, has member elevating contact therewith and is actuated by the rotation of the record to move the member and arm outward a predetermined extent and then to turn the element to lower the member, and escapement mechanism coacting with said element to control its rotation and automatically operable at predetermined points 10 in the inward and outward movements of said arm to permit predetermined rotary movements of the element.

24. In a phonograph, a horizontally and vertically movable member carrying a stylus, a rotating record subjacent to said member, rotatable member elevating means carried by said member and operable, when in one position to permit the stylus of said member to stand free from engagement with the record and when in another position to engage the record, said means being operable 50 both by gravity and by the rotation of the record to move from released position to record engaging position and being operable by the rotation of the record to move from record engaging to released position, and 55 means automatically operable to periodically engage and release said element to permit intermittent movements thereof. 60

22. In a phonograph, a stylus carrying member mounted for horizontal and vertical movements, a subjacent rotating record support, and mechanism connected to said member and automatically operable, at a predetermined point in a horizontal stroke of the member, to engage and coöperate with 20 a record on said support to raise the member to release its stylus from the record, swing the member outward a predetermined extent, and then lower the member to engage its stylus with the record, the record engaging part of said mechanism comprising a 25 rotatable element which is rotatable in one direction only to engage and release the record.

25. In a phonograph, a horizontally and vertically movable stylus carrying member, a rotating record subjacent to said member, a rotatable member elevating element connected to said member and operable, when at one point in its rotation, to coact with the record to elevate said member relative thereto, move it outward and then to rotate 30 to lower the member into playing position, 35 record on the support, and means both for counterbalancing the weight of the mechanism on the member and for retarding the record engaging movement of the stylus carrying member. 75

In testimony whereof I have hereunto signed my name to this specification. 80

HUBERT A. MYERS.
